UNITED STATES PATENT OFFICE

165,701

ARTIFICIAL CHRISTMAS TREE

Garland B. Smith, Madison, Wis.

Application October 10, 1949, Serial No. 5,398

Term of patent 14 years

(Cl. D29—1)

To all whom it may concern:

Be it known that I, Garland B. Smith, a citizen of the United States, residing at Madison, in the county of Dane and State of Wisconsin, have invented a new, original, and ornamental Design for Artificial Christmas Tree, of which the following is a specification, reference being had to the accompanying drawing, forming part thereof.

The single figure is a perspective view of an artificial Christmas tree showing my new design.

My design comprises a cone of expanded metal foil having tapered, double ruffles of said expanded foil extending from the base to the tip in serpentine waves, as shown.

I claim:

The ornamental design for an artificial Christmas tree, as shown and described.

GARLAND B. SMITH.
